UNITED STATES PATENT OFFICE

HORACE DRUMMOND BLACK, OF UXBRIDGE, ENGLAND

TICKET ISSUING MACHINE

Application filed October 30, 1929, Serial No. 403,570, and in Great Britain November 14, 1928.

This invention is for improvements in ticket issuing machines wherein a printing mechanism is operable to select automatically a character or group of characters (for example, numerals) from a range and print the same upon a ticket.

According to the present invention there is provided a ticket printing and issuing machine wherein a rotary printing cylinder is arranged to carry one or more type wheels, operable by setting mechanism, to be moved automatically into a selected position relatively to the printing cylinder as the same rotates and prior to the printing operation.

Further, according to the present invention there is provided a ticket issuing and printing machine wherein mechanism, operable by setting mechanism, is arranged to engage with a ticket severed from a web and feed the same forwardly through the machine in such a manner that the ticket receives a printed impression from one or more type wheels operable by the said setting mechanism to be moved automatically into a selected position prior to the ticket receiving an impression therefrom.

Again, according to the present invention there is provided a ticket printing and issuing machine wherein a printing mechanism is arranged to carry one or more type wheels operable by setting mechanism to be moved automatically into a selected position relatively to the printing mechanism prior to the printing operation and to feed the material to be printed upon forwardly as each impression is being printed thereon.

In order that the invention may be clearly understood reference is directed to the accompanying drawings, in which:—

Figure 1 illustrates a sectional front elevation of a ticket issuing machine constructed according to this invention, and showing part of the front casing removed.

Figure 2 is a side elevation of Figure 1 with the side casing removed.

Figure 3 is a sectional plan view, drawn to an enlarged scale, of Figure 1.

Figure 4 is a part sectional elevation of the opposite side of the machine to that shown in Figure 2.

Figure 5 is a view similar to Figure 4 but with the parts in a different position.

Figure 6 is a vertical section on the line 6—6 of Figure 3.

Figure 7 is a view similar to Figure 6 with the parts thereof in a different position.

Figure 8 is a section on the line 8—8 of Figure 3.

Figure 9 is a sectional view of the printing cylinder.

Figure 10 is a section of the type wheel 57 illustrated in Figure 9.

Figure 11 is a section on the line 11—11 of Figure 4 but with the parts shown in a position hereinafter described.

Figure 12 is a section on the line 12—12 of Figure 4, and

Figure 13 is a section of a detail on the line 13—13, Figure 3.

Referring to the drawings a series of operating keys 1, 1 are pivotally mounted upon a spindle 2, carried by frame members 3, 3¹. Each of the keys 1 is provided with an extension 4 which is normally arranged to lie beneath a universal clutch bar 5, which is connected by links 6 to a rod 7 rigidly mounted in the arms of a stirrup member 8 secured to a spindle 9 mounted in bearings in the frame members 3, 3¹. The rod 7 is arranged to extend through an aperture 10 in the frame member 3 and is secured to one end of an arm 11 the other end of which is secured to the spindle 9 which is arranged also to project through the frame member 3. The arm 11 is connected to a spring 12 (Figure 2) which normally ensures that the clutch bar 5 abuts against stops 13 fixed to the frame of the machine. A stop 14 provided on the arm 11 is arranged normally to engage with an arm 15 keyed to a shaft 16 which carries a type cylinder 17. Pivoted to the arm 15 is a catch 18 provided at one end thereof with a tooth 19. The catch 18 is normally maintained by the stop 14 (against the influence of a spring 20) in the position shown in Figure 2.

The end of the spindle 9 remote from the arm 11 has rigidly secured thereto a switch actuating arm 22 provided with a pin 23 and also pivotally supports a switch arm 21

which is normally held in engagement with the pin 23 by a spring 24. The depression of any one of the keys 1 causes the extension 4 thereof to engage the universal clutch bar 5 and lift the same clear of the stops 13. The spring 12 thereupon moves the arm 11, together with the bar 7 and clutch bar 5 in the direction of the arrow *b* (Figure 2) until the arm 11 contacts with a stop 12¹, whereupon the bar 7 and clutch bar 5 assume the position shown in Figure 7. Further, any movement of the arm 11 effects a partial rotation of the spindle 9 which causes the pin 23 on the arm 22 (Figure 4) to close the switch, (Figure 5) and complete the electrical circuit of a driving motor 27.

The movement of the arm 11 also moves the stop 14 out of engagement with the arm 15 and the catch 18 and permits the spring 20 to move the tooth 19 on the catch 18 into engagement with one of a series of teeth 28 formed on a sprocket wheel 29 driven by gearing from the spindle of the motor 27 and thereby cause the shaft 16 to rotate in the direction of the arrow *c* (Figure 6).

The bar 7 has connected thereto a locking bar 30 which, upon the movement of the arm 11, is moved into engagement with the underside of the extension 4 of a depression key 30 and maintains the same in the depressed position whilst at the same time engaging with the upper side of the extension 4 of the remaining keys so as to lock the same against depression.

As the shaft 16 rotates a cam 31 mounted thereon causes a roller 32 carried by an arm 33 to move towards the axis of rotation of the shaft 16. The arm 33 is carried upon a pivot 33_a fixed relatively to the machine. Connected to the free end of arm 33 are two links 34 the free ends of which are arranged in engagement with pins 35 carried by arms 36 of setting bars 37 and 38. The setting bars 37 and 38 are always urged towards one another by a spring 39 (Figure 7) so that upon the described movement of the cam 31 the setting bars 37 and 38 are moved about spindles 40 by the spring 39. Each key is provided with two abutments 41, 42 arranged respectively above and below the axis of rotation thereof and which, when a key is depressed, are moved into the path of movement of the setting bars 37, 38 to arrest the movement of the same in the position indicated, for example, by dot and dash positions of the setting bars in Figure 7. The length of the abutments 41—42, vary with each key, thus ensuring that the amount of movement of the setting bars varies with the key that is depressed.

Pivoted upon the spindles 40 are two bell crank levers 43 the arms 44 of which are normally maintained, by means of springs 46, in contact with bars 45 integral with the setting bars 37, 38. The arms 47 of the bell crank

levers 43 are arranged in engagement with one limb 48 of a bell crank lever 48, 49, pivotally mounted upon the machine frame at 50 (Figure 3).

Each of the bell crank levers 48, 49 carry at the end of the arm 49 a yoke 51 arranged in engagement with an annular groove 52 formed in a sleeve 53 slidable axially upon the shaft 16. The sleeves 53 each carry a guide 54 in engagement with a guide rod 55 carried on the printing cylinder 17 so that the said sleeves are always maintained in fixed rotational relationship with the printing cylinder 17. The sleeves 53 are each provided with radial stops 56 for a purpose hereinafter described.

It will be observed from the foregoing that the extent of the movements of the sleeves 53 on the shaft 16 is determined by the key which is depressed.

Pivoted upon the printing cylinder are two type wheels 57, 58 each having a series of type faces thereon. In the arrangement shown in the drawings each type wheel has 10 facets and inscribed upon the facets of the type wheel 57 are the numerals from 0 to 9, whilst the facets of the type wheel 58 have inscribed thereon an inscription "No.", the numerals 1 to 8, and one blank face. Fixed to each of the type wheels 57, 58 are stepped cylinders 59 each having a series of abutments 60 corresponding in number and disposition to the facets on the type wheels 57 and 58. The stepped cylinders 59 are maintained in engagement with the radial stops 56 by coiled springs 61, housed in the type wheels 57 and 58 in the manner indicated in Figure 10.

In the normal position of the stops 56 and the stepped cylinders 59 the type facets "No." and "0" are maintained adjacent to one another so that if the printing cylinder 17 is rotated the said facets would receive a supply of ink from an ink roller 117.

When a key is depressed the cylinder 17 commences to rotate and one or both of the sleeves 53 is or are moved along the shaft 16. The corresponding stepped cylinders 59 are thereupon released and rotated by the spring 61 until the abutments 60 corresponding with the key depressed engage with the corresponding radial stops 56 which arrest the movement of the type wheels to bring the numbered type facets corresponding to the key depressed into register with the surface of revolution generated by the printing cylinder.

The continued rotation of the printing cylinder 17 causes the type wheels 57, 58 and other type members 17¹ and 72 carried by the printing cylinder to contact with the ink roller 117 and thereafter engage and feed forwardly a portion severed from a ticket web automatically fed, in a manner hereinafter described into engagement with an impression 130

roller 25. The ticket is thereby printed and at the same time moved through a guide 25¹ into engagement with a roller 118 carried upon a spindle 119 rotatably mounted in bearings in the machine frame. The spindle 119 carries a pulley 120 which is operably connected by means of a spring belt 121 to a pulley carried upon a sprocket wheel 122 arranged in mesh with the driving gear which connects the motor 27 with the shaft 16 (Figure 2). The rotation of the roller 118 causes the ticket to be delivered through a slot 25² in the cover of the machine.

In the example illustrated in Figure 7 the key "35" has been depressed and the setting bars 37, 38 have been moved into the position indicated by the dot and dash lines thereby moving the sleeves 53 and the radial stops 56 into the positions indicated by the dot and dash lines in Figure 3, to permit the stepped cylinders 59 to move the type wheels 57, 58 until the facets corresponding to numerals "3" and "5" are brought adjacent to one another and into register with the surface of revolution generated by the printing cylinder.

Further, when a key is depressed stops 65 are moved out of engagement with arms 64 provided upon a toothed quadrant 63.

As the type wheels 57, 58 are being rotated by the springs 61 pinions 62 carried thereby are arranged to move the toothed quadrants 63 and arms 64 relatively to the printing cylinder whereby the type wheels after each printing operation are returned to the position wherein the facets display the inscription "No." and "0".

To effect this return movement a cam 66 mounted upon the shaft 16 (Figure 8) comes into operation, towards the latter part of each complete revolution of the printing cylinder 17, to engage an arm 67 mounted upon the stirrup member 8 and rock the stirrup member about the axis of the shaft 9 and thereby move the stop members 65 into the path of the arms 64 to arrest the movement of the same and thereby cause the sectors 63, 63 to rotate the type wheels 57, 58 until the inscription "No." and the numeral "0" are arranged adjacent to one another and in register with the surface of revolution generated by the printing cylinder 17. At about the same time the rotation of the shaft 16 causes the cam 31 to move the setting bars 37, 38 through the medium of the links 34 back to the normal position, which permits the springs 46 to actuate the bell crank levers 43, and 48, 49 to move the sleeves 53 back to the position indicated in full lines in Figure 3 where the stop members 56 abut against the steps of the cylinders 59 and ensure that the type wheels 57 and 58 are maintained in the position set out above. The actuation of the stirrup member 8 moves the locking bar 30 to the left in Figure 7, which permits the

spring 2¹ to return the depressed key into the normal position. Further, the movement of the stirrup member 8 also moves the universal clutch bar 5 to the left in Figure 7 clear of the key extensions 4 so that the keys 1 cannot move the clutch bar 5.

Immediately the cam 66 engages the arm 67, the spindle 9 is rocked about the axis thereof and moves the arm 22 and its associated pin 23 out of engagement with the switch arm 21 into the position indicated in dot and dash lines in Figure 5 but simultaneously a cam 68 mounted upon the shaft 16 co-acts with a roller 69 mounted upon an extension 70 of the switch arm 21 in the manner indicated by dot and dash lines in Figure 5 so as to maintain the switch in a closed position.

When the stirrup member 8 is in the position indicated above the stop 14 is arranged in the path of the arm 15 and the catch 18 so that the continued movement of the shaft 16 causes the catch 18 to be declutched from the sprocket wheel 29 and the arm 15 will thereafter abut against the stop 14 and arrest the movement of the printing cylinder.

As the printing cylinder 17 is arrested, the arm 67 is released from the cam 66 and so frees the stirrup member 8, which under the influence of the spring 12 returns to its initial position and moves the clutch bar 5 above the extensions 4 of the keys 1, and simultaneously the cam 68 releases the switch arm 21 and permits the spring 24 to move the same so as to open the circuit of the motor 27.

The feeding of ticket blanks into operative relationship with the printing mechanism above described is accomplished in the following manner.

A web of material 103 in the form of a reel is mounted upon a spindle 103¹ revolvably mounted in a bracket 103² fixed in the lower portion of the machine casing. (Figures 1 and 2.)

The free end of the web 103 is initially fed by hand into the lower end of a guide 104 (Figure 6) and thence into a guide 111 where the same engages with the impression roller 25.

As the free edge of the web is moved into engagement with the impression roller 25 the same engages with a pair of abutments 112, formed upon a pivotally mounted member 113 arranged normally to extend across the guide 111. The free edge of the web moves the member 113 about its pivot in the direction of the arrow *d* (Figure 6) into the position indicated in Figure 7, against the influence of a spring (not shown).

Connected to the member 113 is one end of a link 114 the other end of which engages with a pin 115 fixed to a stop member 26 pivotally mounted upon a spindle 40 carried by the frame of the machine. If a web of material is located in engagement with the roller 25 the stop member is moved into the posi-

tion indicated in Figure 7. On the other hand the stop member 26 is arranged to extend above the universal clutch bar 5 and prevent the same from being raised unless a web of material is disposed in engagement with the impression roller 25.

Thus assuming that the free edge of the web is in engagement with the roller 25, and that one of the keys is depressed the machine commences to operate, and a guillotine 110 actuated by a pin 108 on a feeding disc 105 driven from the main drive severs a ticket from the web. After a predetermined interval the disc 105 engages with the free end of the severed web and feeds the same forwardly by an amount equal to the length of one ticket, whilst the printing cylinder 17 in co-operation with the roller 25 prints and feeds the severed ticket into engagement with the ejection roller 118 in the manner hereinbefore described.

In order to prevent more than one key at a time being depressed a row of balls 71 is arranged adjacent the lower edges of the keys 1 so as to provide a total free space between all the balls sufficient to permit only of the admittance of one key lever.

An additional type wheel 72 having a plurality of type faces arranged around the periphery thereof is pivotally mounted upon the type cylinder 17 and is provided with a ratchet wheel 73 having teeth equal in number to the type faces. The ratchet wheel 73 co-acts with a spring actuated detent 74 (Figure 6) which ensures that one type face is always in register with the surface of revolution generated by the printing cylinder. A pin 76 is fixed to a spindle 75 which is rotatably mounted in bearings in the frame members 3, 3¹. The path of rotation of the pin 76 is in the plane of rotation of the ratchet wheel 73 and is arranged to intercept the same. The spindle 75 is provided at one end with a bevel wheel 77 arranged in mesh with a second bevel wheel 78 carried at one end of a spindle 79 mounted in bearings in the frame member 3¹. The free end of the spindle 79 extends through the front of the casing of the machine and is provided with a knob 80. The arrangement is such that upon one complete rotation of the knob 80 the spindles 79 and 75 cause the pin 76 to engage with the ratchet wheel 73 and move the type wheel 72 so as to bring the next adjacent type face on the type wheel 72 into register with the surface of revolution generated by the printing cylinder. A pin 82 mounted upon the shaft 79 (Figure 11) is so arranged that when the latter is rotated the pin is moved into engagement with a pivotally mounted notched member 83 operable to produce the well known Geneva movement. The member 83 is arranged to rotate an indicator 81 provided on the exterior of the machine (Figure 1) to indicate which of the type faces of the type

wheel 72 is in register with the surface of revolution generated by the printing cylinder 17.

The notched member 83 is provided with a pin 84 which at the end of one complete revolution of the notched member 83 and the type wheel 72 engages with one end of a lever 85 pivoted to the machine frame (Figure 11) and prevents further rotation of the knob 80.

The lever 85 which is arranged so as to be accessible only by an authorised person, may be moved manually against the influence of a spring, in the direction of the arrow (Figure 11) and out of engagement with the pin 84 so that the knob 80 may be rotated to move the type wheel 72 through a further revolution.

As it is essential that the machine cannot be operated whilst the type wheel is being moved, the spindle 79 is provided with a cam disc 87 having two diametrically disposed notches 88 and 89. In the normal position of operation of the machine the notch 88 is arranged to engage with one end of a plunger 90, slidably mounted in the frame of the machine and which is held in engagement with the cam 87 through the medium of a spring 91 (Figure 12). The other end of the plunger 90 forms an abutment for one end of the row of balls 71 and in the position shown in Figure 12 ensures the free space between the balls previously referred to. It will be observed, however, that when the knob 80 is operated and the cam 87 rotates in the direction of the arrow (Figure 12) the plunger 90 is moved by the cam and takes up the free space between the balls 71 and prevents the depression of a key, whilst on the other hand the depression of a key 1 prevents the rotation of the knob 80.

The notch 89 is made equal to half the depth of the notch 88 and is provided so as to permit the operator to rotate the spindle 79 in the reverse direction if he should overrun the correct position, but prevents the spindle being rotated more than half a revolution in the reverse direction.

Two counters 92, one serving as a check against the other, are provided for the purpose of furnishing a record of the total number of tickets issued by the machine. The actuating pin of each counter is connected to one end of a link 93, the other end of which is provided with a slot 102 arranged to engage with a rod 95 carried by a pivoted stirrup member 96 and which is operably connected to an eccentric 97 mounted upon the shaft 16 (Figure 3). The links 93 are normally maintained in the position indicated in Figure 6 by the rod 95 acting against the influence of springs 94. Upon the rotation of the shaft 16 the eccentric 97 moves the rod 95 (Figure 13) which permits the springs 94 to move the links 93 so that extensions 98 are moved through apertures 99 in a pivoted member 100. 130

The member 100, however, is arranged under the control of a "test" key 1¹ which when operated to test the machine moves the apertures out of line with the extensions 98 of the link 93 so as to prevent the operation of the counters for a test operation. When the link 93 is moved in the reverse direction by the eccentric 97 the actuation of the counters 92 is completed. The test key 1¹ hereinbefore referred to, is connected to a link 101 pivoted at one end to the key and at the other end to the member 100 so that upon the depression of the test key the said member is moved as hereinbefore described.

It will be observed that the type surfaces of the type cylinder 17 are relatively widely spaced around a circle of comparatively large diameter, but that as the feeding of the ticket forwardly during the printing process is accomplished solely by the frictional engagement of the type surfaces with the ticket, the impressions received by the ticket will be disposed thereon in substantially close proximity to one another.

What I claim and desire to secure by Letters Patent:—

1. In a ticket printing and issuing machine, the combination of a rotatable printing cylinder, at least one type member provided with a plurality of type faces of different denominations movably mounted upon said cylinder, setting mechanism operable to control the differential movement of said type member relatively to the said printing cylinder as the same rotates, and manipulating means operable to actuate said setting mechanism to select one type face of the said member and cause a ticket to be printed and issued bearing an impression from the selected type face.

2. In a ticket printing and issuing machine, the combination of a rotatable printing cylinder, at least one type member provided with a plurality of type faces of different denominations movably mounted upon said cylinder, setting mechanism operable to control the differential movement of said type member relatively to said printing cylinder as the same rotates, a series of keys, any one of which is operable to actuate said setting mechanism and cause a ticket to be printed and issued, bearing an impression from the type member corresponding to the key operated.

3. In a ticket printing and issuing machine, the combination of a printing element and controlling means therefor, a type member movably mounted upon said element and provided with a plurality of type faces of different denominations, setting mechanism arranged to control the differential movement of said type member, manipulating means operable to actuate said setting mechanism to select one type face of said member and to cause the said printing element to engage with a ticket severed from a web to feed the same forwardly through the machine so that a tick-

et is printed and issued bearing at least the impression corresponding to the selected type face.

4. In a ticket printing and issuing machine, the combination of a printing element and controlling means therefor, a type member 70 movably mounted on said element and provided with a plurality of type faces of different denominations, setting mechanism operable to control the differential movement 75 of said type member, a series of keys, any one of which is operable to actuate said setting mechanism and to cause the said printing element to engage with a ticket severed from a web and to feed the same forwardly through 80 the machine so that a ticket is printed and issued bearing an impression from said type member corresponding to the key operated.

5. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally 85 maintaining one of said steps in engagement with a stop slidably mounted on said printing cylinder, setting mechanism arranged to control the differential movement of said stop relatively to said stepped cylinder, manipulating means operable to actuate said setting mechanism to select a type face of said member by movement of said stop so that the yielding control rotates the said type member and stepped cylinder until the selected type face is in alignment with the printing surface of said printing cylinder and mechanism operable automatically to return said type member to normal position 90 95 100 after a ticket has received an impression 105 from the selected type face.

6. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism 110 115 to move said stop so that the yielding control rotates the said type member and stepped cylinder until a selected type face corresponding to the key operated 120 is in alignment with the printing surface of said printing cylinder and mechanism operable automatically to return said type member to normal position after a ticket has received an impression 125 130 from the selected type face.

7. In a ticket printing and issuing machine the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, an operative connection between said stop and a movable member maintained in a normal position against a yielding control by a cam rotated by the printing mechanism and operable to release said member, a series of keys each provided with a differential abutment normally arranged out of the path of movement of said movable member and operable upon an actuation of a key to be moved into the path of said member so as to limit the movement thereof when released by the cam for the purpose specified. 70

8. In a ticket printing and issuing machine the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, an operative connection between said stop and a movable member maintained in a normal position against a yielding control by a cam rotated by the printing mechanism and operable to release said member, a series of keys each provided with a differential abutment normally arranged out of the path of movement of said movable member and operable upon an actuation of a key to be moved into the path of said member so as to limit the movement thereof and of the stop when released by the cam so that the first said yielding control rotates the said type member and stepped cylinder until a selected type face corresponding to the key operated is aligned with the printing surface of the said printing cylinder and mechanism operable automatically to return said type member and stop to normal position after a ticket has received an impression from the selected type face. 80

9. In a ticket printing and issuing machine the combination of a rotatable printing cylinder, at least one type member provided with a plurality of type faces of different denominations movably mounted upon said cylinder, setting mechanism operable to control the differential movement of said type member relatively to said printing cylinder as the same rotates, a series of keys, any one of which is operable to actuate said setting mechanism and means to cause a ticket to be printed and issued bearing an impression from a selected type face of the said type 85

member corresponding to the key operated, means for locking an operated key in the operated position and means for releasing said key after said type face has impressed a ticket. 90

10. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism to move said stop so that the yielding control rotates the said type member and stepped cylinder until a selected type face corresponding to the key operated is in alignment with the printing surface of said printing cylinder and mechanism operable automatically to return said type member to normal position after a ticket has received an impression from the selected type face, means for locking any key in an operated position and means for releasing the same after the said type face has impressed a ticket. 95

11. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, an operative connection between said stop and a movable member maintained in a normal position against a yielding control by a cam rotated by the printing mechanism and operable to release said member, a series of keys each provided with at least one differential abutment normally arranged out of the path of movement of said movable member and operable upon an actuation of a key to be moved into the path of said member so as to limit the movement thereof, and of the stop when released by the cam so that the yielding control rotates the said type member and stepped cylinder until a selected type face corresponding to the key operated is aligned with the printing surface of the said printing cylinder and mechanism operable automatically to return said type member and stop to normal position after a ticket has received an impression from the selected type face, means for locking any key in an operated position and means for releasing the same after the said type face has impressed a ticket. 100

12. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism operable to control the differential movement of said type member relatively to said printing cylinder as the same rotates, a series of keys, any one of which is operable to actuate said setting mechanism and means to cause a ticket to be printed and issued bearing an impression from a selected type face of the said type 105

member corresponding to the key operated, means for locking an operated key in the operated position and means for releasing said key after said type face has impressed a ticket. 110

13. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism operable to control the differential movement of said type member relatively to said printing cylinder as the same rotates, a series of keys, any one of which is operable to actuate said setting mechanism and means to cause a ticket to be printed and issued bearing an impression from a selected type face of the said type 115

member corresponding to the key operated, means for locking an operated key in the operated position and means for releasing said key after said type face has impressed a ticket. 120

14. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism operable to control the differential movement of said type member relatively to said printing cylinder as the same rotates, a series of keys, any one of which is operable to actuate said setting mechanism and means to cause a ticket to be printed and issued bearing an impression from a selected type face of the said type 125

member corresponding to the key operated, means for locking an operated key in the operated position and means for releasing said key after said type face has impressed a ticket. 130

chine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism arranged to control the differential movement of said stop relatively to said stepped cylinder, manipulating means operable to actuate said setting mechanism to select a type face of said member by movement of said stop so that the yielding control rotates the said type member and stepped cylinder until the selected type face is in alignment with the printing surface of said printing cylinder, a pinion mounted on said type member and arranged in mesh with a toothed segment pivotally mounted on said printing cylinder and means operable automatically to rotate said segment to return the said type member to the normal position after a ticket has received an impression from the selected type face.

13. In a ticket printing and issuing machine the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism to move said stop so that the yielding control rotates the said type member and stepped cylinder until a selected type face corresponding to the key operated is in alignment with the printing surface of said printing cylinder, a pinion mounted on said type member and arranged in mesh with a toothed segment pivotally mounted on said printing cylinder and means operable automatically to rotate said segment to return the said type member to normal position after a ticket has received an impression from the selected type face.

14. In a ticket printing and issuing machine the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, an operative connection between said stop and a movable member maintained in a normal position against a yielding control by a cam rotated by the printing mechanism and operable to release

said member, a series of keys each provided with a differential abutment normally arranged out of the path of movement of said movable member and operable upon an actuation of a key to be moved into the path of said member so as to limit the movement thereof, and of the stop, when released by the cam, so that the yielding control rotates the said type member and stepped cylinder until a selected type face corresponding to the key operated is aligned with the printing surface of the said printing cylinder, a pinion mounted on said type member and arranged in mesh with a toothed segment pivotally mounted on said printing cylinder and means operable automatically to rotate said segment to return the said type member to the normal position after a ticket has received an impression from the selected type face.

15. In a ticket printing and issuing machine, the combination of a rotatable printing cylinder, at least one type member provided with a plurality of type faces of different denominations pivotally mounted upon said cylinder, a stepped cylinder rotatable with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism to move said stop so that the yielding control rotates the said type member and stepped cylinder until a selected type face corresponding to the key operated is in alignment with the printing surface of said printing cylinder, a universal bar operable by each key to actuate the printing mechanism, an abutment operatively connected to said bar and normally disposed in the path of movement of a toothed segment pivotally mounted to the said printing cylinder, a pinion on the said type member arranged in mesh with said segment, means for moving the abutment out of the path of the segment prior to a printing operation and means for restoring the abutment to the normal position prior to the completion of a printing operation for the purpose specified.

16. In a ticket printing and issuing machine the combination of a rotatable printing cylinder, at least two type wheels each provided with a plurality of type faces of different denominations pivotally mounted upon said cylinder independent of one another, a stepped cylinder rotatable with each of said wheels and a yielding control for each wheel normally maintaining one of the steps of the corresponding stepped cylinder in engagement with one of a pair of stops independently slidably on said printing cylinder, setting mechanism arranged to con-

- trol the differential movement of said stops relatively to said stepped cylinders, a series of keys any one of which is operable to actuate said setting mechanism to move at least one of said stops so that the yielding 5 control or controls rotates the said type wheel or wheels and stepped cylinder or cylinders until a selected type face upon each wheel corresponding to the key operated is aligned with the printing surface of the said 10 printing cylinder, a universal bar operable by each key to actuate the printing mechanism, at least a pair of abutments operatively connected to said bar and each normally disposed in the path of movement of a corresponding 15 toothed segment pivotally mounted to the said printing cylinder, a pinion on each of said type wheels arranged in mesh with one of said segments, means for moving the abutments out of the path of the segments prior to a printing operation and 20 means for restoring the abutments to the normal position prior to the completion of a printing operation for the purpose specified.
17. In a ticket printing and issuing machine, the combination of a rotatable printing cylinder, at least two type wheels each provided with a plurality of type faces of different denominations independently pivotally mounted upon said cylinder, a stepped cylinder rotatable with each of said type wheels, a yielding control for each type wheel arranged normally to maintain one of said steps of each stepped cylinder in engagement 25 with one of at least a pair of stops independently slidable on said printing cylinder, an operative connection between each of said stops and one of a corresponding number of movable members maintained in a normal 30 position against a yielding control by a cam rotated by the printing mechanism and operable to release said members, a series of keys each provided with at least two differential abutments normally arranged out of the 35 paths of movement of said movable members, each abutment being arranged upon an actuation of a key to be moved into the path of one of said movable members so as to limit the movement thereof and of the corresponding 40 stop when released by the cam so that the first said yielding controls rotate the said type wheels and stepped cylinders until a selected type face upon each of the said wheels corresponding to the key operated, is 45 aligned with the printing surface of the said printing cylinder, a pinion mounted on each of said type wheels and arranged in mesh with one of a corresponding pair of toothed segments pivotally mounted on said printing 50 cylinder and means operable automatically to rotate said segments to return the said type wheels to the normal position after a ticket has received an impression from each of the selected type faces.
18. In a ticket printing and issuing ma- 55 chine, the combination of a rotatable printing cylinder, at least one type member provided with a plurality of type faces of different denominations pivotally mounted upon said cylinder, a stepped cylinder rotatable 60 with said type member, a yielding control normally maintaining one of said steps in engagement with a stop slidably mounted on said printing cylinder, setting mechanism arranged to control the differential movement 65 of said stop relatively to said stepped cylinder, a series of keys, any one of which is operable to actuate said setting mechanism to move said stop so that the yielding control rotates the said type member and stepped 70 cylinder until a selected type face corresponding to the key operated is in alignment with the printing surface of said printing cylinder, a universal bar operable by each key to close a switch for a driving motor for the 75 machine and to actuate a clutch mechanism to effect a single rotation of the printing cylinder, an abutment operatively connected to said bar and normally disposed in the path 80 of movement of a toothed segment pivotally mounted to the said printing cylinder, a pinion on the said type member arranged in mesh with said segment, means for moving the abutment out of the path of the segment prior to a printing operation and means 85 for restoring the abutment to the normal position prior to the completion of a printing operation for the purpose specified.
19. In a ticket printing and issuing ma- 90 chine, the combination of a rotatable printing cylinder, at least one type member provided with a plurality of type faces of different denominations pivotally mounted upon said cylinder, a stepped cylinder rotatable 95 with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism to move said stop so that the yielding control rotates the said type member and stepped 100 cylinder until a selected type face corresponding to the key operated is in alignment with the printing surface of said printing cylinder, a universal bar operable by each key to close a switch for a driving motor for the 105 machine and to actuate a clutch mechanism to effect a single rotation of the printing cylinder, an abutment operatively connected to said bar and normally disposed in the path of movement of a toothed segment pivotally mounted to the said printing cylinder, a pinion on the said type member arranged in mesh with said segment, means for moving the abutment out of the path of the segment prior to a printing operation and means 110 for restoring the abutment to the normal position prior to the completion of a printing operation for the purpose specified.
18. In a ticket printing and issuing ma- 115 chine, the combination of a rotatable printing cylinder, at least one type member provided with a plurality of type faces of different denominations pivotally mounted upon said cylinder, a stepped cylinder rotatable 120 with said type member, a yielding control normally maintaining one of said steps in engagement with a stop slidably mounted on said printing cylinder, setting mechanism arranged to control the differential movement of said stop relatively to said stepped cylinder, a series of keys, any one of which is operable to actuate said setting mechanism to move said stop so that the yielding control rotates the said type member and stepped 125 cylinder until a selected type face corresponding to the key operated is in alignment with the printing surface of said printing cylinder, a universal bar operable by each key to close a switch for a driving motor for the 130 machine and to actuate a clutch mechanism to effect a single rotation of the printing cylinder, an abutment operatively connected to said bar and normally disposed in the path of movement of a toothed segment pivotally mounted to the said printing cylinder, a pinion on the said type member arranged in mesh with said segment, means for moving the abutment out of the path of the segment prior to a printing operation and means for

restoring the universal bar and abutment to the normal position prior to the completion of the printing operation to effect rotation of the said segment and type member to the normal position and to open the said switch.

- 5 20. In a ticket printing and issuing machine the combination of a printing element and controlling means therefor, a type member movably mounted on said elements and provided with a plurality of type faces of 70
10 different denominations, setting mechanism arranged to control the differential movement of said type member, manipulating means operable to actuate said setting mechanism to select one type face of said member and to 75
15 cause the said printing element to engage with a ticket severed from a web to feed the same forwardly through the machine so that a ticket is printed and issued bearing at least an impression from the selected type face, 80
20 means arranged to co-act with the leading edge of said ticket prior to a printing operation and operatively connected to means arranged to lock the machine against operation until said leading edge is moved into a pre- 85
25 determined position.

21. In a ticket printing and issuing machine the combination of a printing element and controlling means therefor, a type member movably mounted upon said element and 90
30 provided with a plurality of type faces of different denominations, setting mechanism arranged to control the differential movement of said type member, manipulating 95
35 means operable to actuate said setting mechanism to select one type face of said member and to cause the said printing element to engage with a ticket severed from a web to feed the same forwardly through the machine so 100
40 that a ticket is printed and issued bearing at least an impression from the selected type face, a movable member normally extending across a guide race for the ticket web and arranged to co-act with the leading edge of 105
45 said web, an operative connection between said movable member and a pivoted stop arranged to control means which prevent an actuation of the manipulating means until the leading edge of said web is moved into a 110
50 predetermined position.

22. In a ticket printing and issuing machine, the combination of a rotatable printing cylinder, at least one type member provided with a plurality of type faces of different 115
55 denominations movably mounted upon said cylinder, setting mechanism operable to control the differential movement of said type member relatively to said printing cylinder as the same rotates, a series of keys, any one of 120
60 which is operable to move a universal bar operatively connected to means arranged to actuate the printing mechanism and each key being arranged to actuate said setting mechanism so as to cause a ticket to be printed 125
65 and issued bearing an impression from the 130

type member corresponding to the key operated, a movable member normally arranged to extend across a guide race for a ticket web to be printed and arranged to co-act with the leading edge thereof, an operative connection between said member and a pivoted stop normally arranged to prevent an actuation of said universal bar by said keys, said stop being moved clear of said universal bar when the ticket web moves said movable member into a predetermined position.

HORACE DRUMMOND BLACK.
